(57) **CLAIM**

The ornamental design for a sun garden light, as shown and described.

DESCRIPTION

FIG. 1 is a front perspective view of a sun garden light, showing my new design;
FIG. 2 is a front view thereof;
FIG. 3 is a rear view thereof;
FIG. 4 is a left side view thereof;
FIG. 5 is a right side view thereof;
FIG. 6 is an enlarged top view thereof;
FIG. 7 is an enlarged bottom view thereof;
FIG. 8 is a perspective view thereof, shown in an alternate configuration; and,
FIG. 9 is an enlarged detail view of area 9 in FIG. 6.
The broken lines in the drawings illustrate the portions of the sun garden light, which form no part of the claimed design. The dash-dot broken lines represent the bounds of the enlarged view and form no part of the claimed design.
